US0D1051159S

(12) **United States Design Patent** (10) **Patent No.:** **US D1,051,159 S**
(45) **Date of Patent:** **** Nov. 12, 2024**

(54) **DISPLAY DEVICE WITH GRAPHICAL USER INTERFACE**

(71) Applicant: **Total Safety U.S., Inc.**, Pasadena, TX (US)

(72) Inventor: **Gunter Jano Emiel Vancraybex**, Bilzen (BE)

(73) Assignee: **Total Safety U.S., Inc.**, Houston, TX (US)

(**) Term: **15 Years**

(21) Appl. No.: **29/933,834**

(22) Filed: **Mar. 21, 2024**

Related U.S. Application Data

(63) Continuation of application No. 29/724,849, filed on Feb. 19, 2020, now Pat. No. 1,025,086, which is a continuation of application No. 16/507,767, filed on Jul. 10, 2019, now Pat. No. 11,328,514.

(57) **CLAIM**
The ornamental design for a display device with a graphical user interface as shown and described.

DESCRIPTION

The FIGURE is a view of the display device with the graphical user interface. The outermost broken line illustrates the display screen, and the remaining broken lines illustrate portions of the graphical user interface. None of the broken lines form part of the claimed design.

1 Claim, 1 Drawing Sheet
